UNITED STATES PATENT OFFICE.

HENRY FUNSCH, OF BROOKLYN, NEW YORK.

ASH-TRAY.

1,201,166.

Specification of Letters Patent. Patented Oct. 10, 1916.

Application filed December 6, 1915. Serial No. 65,368.

To all whom it may concern:

Be it known that I, HENRY FUNSCH, a citizen of the United States, residing at Brooklyn, in the county of Kings and State of New York, have invented certain new and useful Improvements in Ash-Trays; and I do hereby declare the following to be a full, clear, and exact description of the invention, such as will enable others skilled in the art to which it appertains to make and use the same.

This invention relates to ash trays and more particularly to that type which may be detachably supported by the edge of a table or the like.

It has for an object to provide an improved construction for an ash tray whereby the ash tray is indirectly supported by the edge of a table so that heated ashes placed therein as from a cigar, cannot mar the polish of the table.

A further object of this invention is the provision of an extension from the ash tray which has its underside provided with a felt or similar covering, for engagement with the upper face of the table near the edge thereof.

A further object of this invention is the provision of an ash tray having an extension formed thereon and having a match holder formed in said extension, said match holder serving as a stop for engaging the edge of the table or the like in the application of the ash tray to the edge of the table.

A further object of this invention is the provision of an improved support for a spring actuated clamp in having the support for some of the bearings of the clamp formed to receive one end of a spring member.

Further objects will be apparent from the following specification, appended claims and drawings, in which—

Figure 1 is a perspective view showing the ash tray applied to the edge of a table, Fig. 2 is a vertical sectional view longitudinally therethrough, Fig. 3 is a perspective view showing the ash tray removed and showing the underside of the ash tray.

The ash tray shown in the accompanying drawings is one of simple construction which may be easily applied to a table, desk, or other piece of furniture near the edge thereof. It has the parts thereof so disposed as to avoid any elevated obstructions rising to a perceptible distance above

the plane of the table or other top as the case may be, and it further positions the ash tray so as to remove the hot ashes or lighted cigars from the woodwork so as to avoid marring the finish of said woodwork. Referring to the drawings, there is shown a section of a piece of furniture such as a table-top 10 upon which the felt pad 11 bears and this felt pad is attached to a stem 12 which supports the ash tray 13. The stem 12 has a portion thereof serrated as at 14 to afford a striking surface for matches and the like, and said stem is further recessed to permit the insertion of a match holder 15 which has the upper edge thereof bent over as at 16 for attachment to the upper face of the stem 12. The ash tray 13 which is of common construction has the flange 17 formed thereabout and this flange 17 is attached to the upper face of the stem 12 as at 18. The rim of the ash tray is also provided with one or more holders 19 for cigars or the like and these holders are so positioned as to dispose the lighted end of a cigar properly over the ash tray 13.

A bracket 20 is secured to the under face of the tray 13 and this bracket comprises a length of metal having the central portion thereof removed as at 21 and then bent upon itself as at 22 to form bearings for a pintle 23 which supports ears 24 of a clamp 25 which is recessed as at 26 to receive the lower end of the match holder 15, and this clamp is bent as at 27 to form the upwardly extending portion 28 which has its upper edge toothed as at 29. The bracket 20 has one portion thereof depressed as at 30 to form a socket into which one end of a spring 31 extends and this spring is bent upon itself as at 32 to afford the resilient extension for engagement with the free end of the clamp 25 as shown.

It is seen that to apply the ash tray to a piece of furniture, the free end of the clamp 25 may be gripped with one of the fingers of the hand which supports the ash tray 13 when said clamp may be swung to permit the stem 12 being slid upon the upper surface of the piece of furniture or the like until the match holder 15 engages the edge of the piece of furniture and then the free end of the clamp 25 may be released to permit the toothed edge 29 to properly engage the underside of the edge of the table-top or the like.

It is apparent that slight modifications

may be made within the scope of this invention without departing from the spirit of the appended claims and the drawing submitted herewith is for illustrative purposes only.

Having thus described my invention, I claim:—

1. In combination with an ash tray, a stem secured thereto, and extending therefrom to overlie the edge of a table top, a bracket secured to said ash tray having resilient extensions therefrom, said bracket having a socket formed therein, by depressing a portion of the metal thereof, a pintle supported by said resilient sections, a clamp pivotally supported by said pintle and a spring carried in said socket for actuating said clamp.
2. In an ash tray of the class described, a tray having a stem extending from one edge thereof to overlie a table top, a clamp coacting with said stem in holding the tray, a bracket carried by said tray on the under face thereof near the edge under said stem,

said bracket comprising a strip of resilient metal bent upon itself to form knuckles, the central portion of said folded end being removed to increase resiliency of said bracket, a pintle carried by the knuckle of said bracket, upturned ears formed on said clamp to receive the ends of said pintle, one of the leaves of said bracket having a depression formed therein, a spring having one end thereof insertible in said depression in bearing relation between said bracket and the free end of said clamp, said clamp having an extension therefrom for manipulation of said clamp, and said spring contacting with said clamp near its free end to afford flexibility of mounting of said clamp on said tray.

In testimony whereof I affix my signature in presence of two witnesses.

HENRY FUNSCH.
